US0D1038033S

(12) **United States Design Patent** (10) **Patent No.:** **US D1,038,033 S**
(45) **Date of Patent:** **** Aug. 6, 2024**

(54) **ELECTRICAL CONNECTOR**

(71) Applicant: **Grundfos Holding A/S**, Bjerringbro (DK)

(72) Inventor: **Jonas Kjær**, Bjerringbro (DK)

(73) Assignee: **Grundfos Holding A/S**, Bjerringbro (DK)

(**) Term: **15 Years**

(21) Appl. No.: **35/515,400**

(22) Filed: **Sep. 26, 2022**

(80) **Hague Agreement Data**

Int. Filing Date: **Sep. 26, 2022**

Int. Reg. No.: **DM/223997**

Int. Reg. Date: **Sep. 26, 2022**

Int. Reg. Pub. Date: **Oct. 21, 2022**

(51) **LOC (14) Cl.** **13-03**

(52) **U.S. Cl.**

USPC **D13/133**; D13/146; D13/147; D13/151

(58) **Field of Classification Search**

USPC D13/133, 146–147, 151, 154–156; D15/7

CPC H01R 13/521; H01R 13/5202; H01R

(57) **CLAIM**

The ornamental design for an electrical connector, as shown and described.

DESCRIPTION

3. Electrical connector

3.1 : Perspective

3.2 : Front

3.3 : Back

3.4 : Top

3.5 : Bottom

3.6 : Left

3.7 : Right

3.8 : Perspective

1. The name of this design product: electrical connector; 2. Purpose of the product with this design: to provide an electrical connection; 3. The main points of the design of the product are: the overall shape of the product; 4. The picture or photo that best shows the main points of the design: reproduction No. 3.1—perspective view.

The broken lines shown in the figures depict portions of the electrical connector that form no part of the claimed design.

1 Claim, 8 Drawing Sheets
